UNITED STATES PATENT OFFICE

2,603,452

PUMP VALVE

Frank R. Spinney, San Mateo, Calif., assignor of sixteen and two-thirds per cent to John Kirk, sixteen and two-thirds per cent to Ollie Jones, thirty per cent to Charles J. Jones, sixteen and two-thirds per cent to Thomas G. Jones, and ten per cent to Richard G. Baender, all of Delano, and five per cent to Charlotte F. Webb, Pasadena, Calif.

Application April 4, 1949, Serial No. 85,465.

2 Claims. (Cl. 251—144)

1

My invention relates to valve structures and particularly to the valve structures of pumps designed for handling liquids containing solid matter which causes improper functioning of valves of previous construction.

An illustrative use of the valve structures of my invention is the making of wines in which the juice pressed out of the grapes in the pressing vats has to be pumped out of the vats. As the liquid to be pumped contains grapeskins and seeds, it frequently happens in the case of valves as previously constructed that such solid matter lodges between the valve and its seat and in the cage to prevent proper opening and full and complete closure of the valve so that the pump is rendered partly or wholly ineffective to circulate the liquid at full pump capacity.

It is an object of my invention to provide a valve construction in which it is practically impossible for the solid matter contained in a liquid being pumped to interfere with the proper functioning of the valve. My valve provides for maximum freedom of flow of liquid and any solid matter entrained therewith around the valve so as to minimize the possibility of such solid matter lodging in the valve structure and preventing its proper closure.

Another object of my invention is to provide a vertically arranged valve structure having a semispherical valve arranged so as to be free to tilt relatively to its seat, in all directions, but which will be returned by gravity into sealing engagement with its seat notwithstanding its tilted position. The tilting movement of the valve is effective to prevent corrosion and scoring of the valve since the area of contact of the valve with the valve seat is continually varying. Also, such tilting movement of the valve when in contact with the valve seat causes the latter to scrape the valve surface free of any accumulations of solid matter thereon, and thus the valve is kept clean to fully and completely close and eliminate the possibility of leakage.

It is also desirable or necessary to dismantle the valve structures from time to time, and it is a further object of my invention to provide a valve structure which comprises a small number of parts which may be very easily and quickly assembled and disassembled.

Another object of my invention is to provide a valve incorporating the features above described and, in addition, one particularly adapted for use in the pumping of light liquids, means being provided therein to accelerate return of the valve to its seat and thereby prevent any

backflow of liquid to the pump, and also prevent chattering or pounding of the valve.

Still further objects and features of my invention will hereinafter appear from the following specification taken in conjunction with the accompanying drawings which illustrate embodiments of the invention at present deemed preferable by me, but it is to be understood that various changes and modifications of parts may be made by those skilled in the art without departing from the scope of the invention as intended to be defined by the appended claims.

In the accompanying drawings:

Fig. 1 is a section through one form of the valve of my invention, taken on the line 1—1 of Fig. 2.

Fig. 2 is a plan view of the valve shown in Fig. 1.

Fig. 3 is an enlarged sectional view taken on the line 3—3 of Fig. 2, showing the parts indicated by the circle 3 in Fig. 1.

Fig. 4 is a perspective view showing the rings seen in Fig. 3 and on a reduced scale.

Fig. 5 is a section similar to Fig. 1 but showing a modified form of the valve.

Fig. 6 is a view showing the retainer ring of Fig. 5 in perspective and on a reduced scale.

In the drawings the numeral 10 indicates generally the valve cage in which is mounted a semispherical valve member generally indicated at 12.

The valve cage provides a preferably tapered and screw threaded end 14 by which the valve cage may be mounted in position in a pipe 15 or other part provided with a mating flared and screw threaded socket. The body of the cage is formed as a ring 18 provided with a sharply angled valve seat 19 extending circumferentially of the valve body.

The valve 12 as shown in Fig. 1 is of a shape to fit accurately on the valve seat in any tilted position it may assume in functioning. Preferably, as shown the valve is formed with a semispherical valve seat engaging area and is sufficiently heavy to make perfect contact around the rim of the valve seat whether tilted or not. I prefer to form the valve as a segment 20 of a relatively thick walled sphere and to provide it with a centrally located boss 22 which is effective to increase the weight of the valve, as well as to adapt it to use with a spring if required as will be later explained. The shape of the valve described will be seen to provide a well balanced and self seating arrangement.

It is an important feature of my invention that the valve is free to tilt in its movements and will

still accurately engage the valve seat for which reason the cage is provided with means to limit the upward movement of the valve and retain it in the valve cage but which do not guide or in any way constrain the valve otherwise.

The limiting means, in the form of the invention shown, comprises three upwardly projecting and equally spaced cage arms 24 extending from, and preferably formed integral with, the body of the cage. The arms 24 are formed adjacent their upper ends with shoulders 24a and with grooves 24b spaced above the shoulders. A retainer ring 26 is positioned upon the shoulders 24a and retained in position by a split spring ring 28 which is sprung into position in the grooves 24b.

The spring ring is preferably provided with holes or depressions 28a adjacent the split in the ring, to enable the ring to be contracted by the use of a special tool, whereby it may be readily withdrawn from engagement in the grooves 24b. The retaining ring 26 is made sufficiently wide to extend inwardly beyond the upper end of the valve.

In the modified form of the invention shown in Fig. 5 the valve cage, valve seat, valve, and spring ring 28 are all identical with the corresponding parts already described with reference to Figs. 1 through 3 and are identified by the same numerals but the retainer ring is of modified construction.

The retainer ring 30 shown in Fig. 5 is formed with a center boss 32 connected by radial arms 33 with the ring as for instance by being cast together therewith. The boss 32 is aligned with boss 22 and a helical spring 34 is positioned on the bosses which is effective to increase the speed with which the valve is returned to its seat and thus to prevent any back flow of liquid to the pump. This valve is intended for use when pumping very light liquids to effect rapid closure of the valve, and to reduce chattering and pounding of the valve on its seat.

It will be noted that the features of the valve structure shown in Figs. 1 through 3 are also present in the valve structure shown in Fig. 5, since the spring 34 is sufficiently flexible to allow the valve to tilt on its seat as the valve is normally free from contact with the vertical arms 24.

In operation the valve shown in either Fig. 1 or Fig. 5 is intermittently raised from its seat by the flow of liquid under the operation of a pump, and in practice tilts in one direction or another in so doing, with the result that a constant variation in the position of the line of contact between the valve surface and the sharp angled circular valve seat take place. Thus the wear of the valve is distributed over a considerable area, and the seat engaging area is kept free from corrosion as well as solid matter accumulations which would occur if the valve always contacted its seat along

the same peripheral line. The valve is very sensitive to variations in fluid pressures since it is not subject to friction caused by the valve guides or valve stems usually provided in pump valve structures.

When the valve requires, for any reason, to be taken apart, the split spring ring can be readily removed from the grooves in the arms of the cage after which the retainer ring and valve may be merely lifted out.

What I claim is:

1. A valve structure comprising a ring shaped body having on the upper edge of its inner periphery a sharp angled valve seat, a semi-spherical valve of concavo-convex formation having its convex side lowermost and normally resting on the valve seat, a boss integral with the valve and positioned on the concave side at the center thereof and operating to center the valve on the seat, a cage comprising upwardly extending arms integral with and equispaced about the periphery of the body, the arms being spaced outwardly from the seat so as to be out of contact with the valve to permit free lifting and tilting of the valve, upwardly facing shoulders adjacent the upper ends of the arms, grooves adjacent the upper ends of the arms and between the shoulders and the ends of the arms, a flat ringlike valve retaining member positioned on the shoulders and a resilient flat split ring engaging the grooves and held thereby so as to hold the retaining member in position, the retaining member serving to limit the upward and opening movement of the valve but allowing free lifting and tilting movement thereof.

2. A valve structure as defined in and by claim 1 wherein the retaining member has a downwardly extending boss adjacent the center thereof, the boss being vertically aligned with but spaced from the boss of the valve and a coil spring surrounding the aligned bosses, the coil spring aiding in forcing the valve to seat.
